UNITED STATES PATENT OFFICE

147,880

DESIGN FOR A PORTABLE BAR AND RADIO COMBINATION

Joseph P. Troyan, Los Angeles, Calif.

Application May 9, 1946, Serial No. 129,503

Term of patent 3½ years

(Cl. D33—19)

To all whom it may concern:

Be it known that I, Joseph P. Troyan, a citizen of the United States, residing at 2323 West Vernon Avenue, Los Angeles, in the county of Los Angeles and State of California, have invented a new, original, and ornamental Design for a Portable Bar and Radio Combination, of which the following is a specification, reference being had to the accompanying drawing, forming a part thereof.

The figure is a perspective view of a portable bar and radio combination, showing my new design.

I claim:

The ornamental design for a portable bar and radio combination, as shown.

JOSEPH P. TROYAN.
